UNITED STATES PATENT OFFICE

2,509,217

COAXIAL SWITCH

William L. Davis, Wray, Colo.

Application August 21, 1947, Serial No. 769,969

9 Claims. (Cl. 178—44)

(Granted under the act of March 3, 1883, as
amended April 30, 1928; 370 O. G. 757)

1

This invention relates to new and useful improvements in a coaxial switch for use as a total or partial disconnector of a coaxial circuit when inserted in said circuit between the antenna and, for instance, a radar set or for any similar application where it is desirable to automatically disconnect a coaxial circuit.

When radar, radio and television sets are in operation, it may be desirable for protective reasons to automatically disconnect the common antenna when a set is turned off, so that the said set will not become damaged by high power electrical impulses incident upon the said antenna. By means of this switch the connection may be merely attenuated at an air-gap instead of being completely disconnected, if it is desirable to leave the antenna partially connected to a set, according to the conditions under which the set is to operate or be maintained in a stand-by condition.

This device operates as a plunger type coaxial switch; by means of a solenoid which, when energized, holds the said switch in the closed position, and when said solenoid is deenergized it allows the said switch to open so that any signals coming in over the coaxial circuit from the connected antenna must pass across a protective air-gap before reaching the set. A coaxial circuit must be protected throughout by a thick covering of "polystirene" insulating material, or equivalent, so that none of the signal impulses become "jammed up" or affected by electrical conditions outside the circuit in the vicinity of the said coaxial cable. Similarly all the circuit conductors within the switch mechanism must be amply protected by insulation throughout. There are many uses for such a remote-controlled switch which will operate in series with other switches so as to make or break a coaxial circuit as the other circuits are made or broken.

The principal object of this invention is to provide a switch that is so constructed as to be suitable for operation in a coaxial circuit.

Another object of this invention is to so design and produce a switch that is suitable for installation in a coaxial circuit and so as to be remote controlled by means of a solenoid operated mechanism.

Still another object of this invention is to so design and produce a remote controlled switch that is amply protected as to insulation throughout its electrical circuit so as to be suitable for use in a coaxial circuit.

A further object of this invention is to provide a remote control coaxial switch that will either

2

attenuate or completely disconnect the circuit.

A still further object of this invention is to provide a remote control switch that is suitably insulated for use in a coaxial circuit and will operate in series with switches of other circuits.

These and other objects of this invention, and the various features and details of the construction, operation and use thereof, are hereinafter more fully set forth and described with reference to the accompanying drawing in which like numbers refer to like parts and in which:

Fig. 1 is an isometric view of a solenoid operated plunger type switch suitable for use in a coaxial circuit and with portions cut away so as to clearly show the interior mechanism.

Referring now to the drawing, numeral 1 designates a solenoid operating mechanism, which through lever 2 operates plunger 3 to which it is connected in slot 4 by means of nuts 5 and washer 6 through spring 7. Nut 5 may be adjusted along the threaded end of plunger 3 so as to adjust the position of plunger 3 when solenoid mechanism 1 is in its open position thereby permitting adjustment of the air gap to be described below.

When the electric circuit controlling solenoid 1 is closed, lever 2 moves plunger 3 up with its contact point 8 into sliding contact with flexible finger contactor 9 that is connected to one side of a coaxial circuit (not shown). Center conductor 10, which moves longitudinally along its axis, has making contact throughout its travel with plunger 11 slidable in rod 12 and held in continual contact with center conductor 10 by means of compression spring 13. Rod 12 carries a bushing 14 in which plunger 11 slides longitudinally. Rod 12 has contact point 15 which makes sliding contact with the coaxial circuit (not shown) by means of finger contactors 16. Said finger contactors 16 are held in and insulated

from connector cap 17, and nut 18 is threaded to connector 17 so as to clamp said connector 17 in housing (not shown). Main connector body 19 is secured to connector cap 17 by threaded ferrule 21 and a screw 20 tapped into body 19 and bearing against the flange of ferrule 21. Insulating bushing 22 is pressed into main connector body 19 and insulates rod 12 from said main connector body 19. Center conductor 10 is slidably held in main connector body 19 by insulating bushing 23.

Connector cap 24 is axially located on main connector body 19 and fastened to said body 19 by threaded ferrule 25. Center conductor 10 is insulated from plunger 3 by bushing 26, which is tapped into nut 27, which screws on to plunger

3. Spring disc 28 contacts a surface 29 of the main connector body 19 when contact point 8 is moved, by means of solenoid 1, into flexible finger connections 9, thus closing all air gaps for the coaxial circuit between flexible finger connections 9 and finger contactor 16.

Metal housing 30 slides over and is fastened to main connector body 19 by screws (not shown) as an outside covering. Flats 31 are for wrench grips.

While a particular embodiment of this invention has been illustrated and described herein, it is not intended that this invention be limited to such disclosure, and changes and modifications may be made and incorporated within the scope of the claims.

The invention described herein may be manufactured and used by or for the Government of the United States of America for governmental purposes without the payment of any royalties thereon or therefor.

What is claimed is:

1. A switch for a coaxial circuit comprising a housing closed at one end by a coaxial terminal plug having the end of the conductor in the center thereof, said housing having an opening in its side closed by another coaxial terminal plug with the end of another conductor therein, a plunger slidably mounted in said housing, a contact conductor mounted on said plunger for slidably making contact with said first terminal conductor end, and another contact conductor insulately mounted in said side opening in continuous slidable contact with said first contact conductor and resiliently held in contact with said other terminal conductor end.

2. A switch for a coaxial circuit as defined in claim 1, wherein said second contact connector includes two telescoping parts urged apart by a compressed spring to provide the continuous contacts defined.

3. A switch for a coaxial circuit as defined in claim 1, wherein said conductor ends comprise flexible fingers, and the contact conductors have matching contact points.

4. A switch for a coaxial circuit as defined in claim 1, operating means for reciprocating said plunger to move said first contact conductor into contact with the corresponding terminal conductor end to close said switch, and to separate said conductor and end to open said switch.

5. A switch for a coaxial circuit as defined in claim 1, operating means for reciprocating said plunger, said means being controlled by a solenoid for remote control and simultaneous operation with other control switch means in said circuit.

6. A switch for a coaxial circuit as defined in claim 1, operating means for reciprocating said plunger, said means comprising an adjustable connection for adjusting the gap between said conductor and end in the open position of said switch for regulating the attenuation of the signals passing said switch.

7. A switch for a coaxial circuit as defined in claim 6, wherein said adjustable connection comprises an operating lever resiliently held against the inside of an adjustable stop on said plunger by the end of a spring the other end of which is fixed to said plunger, whereby resilient closing of the switch and positive adjustable opening thereof is provided.

8. A switch for a coaxial circuit comprising a housing having an opening in its side and at one end thereof, coaxial terminal plugs for closing the openings, each of said plugs having a central conductor, a plunger slidably mounted in the other end of said housing and having a conducting contact thereon for contacting the conductor of the end plug, and a conductor insulately mounted in said side opening for connecting said conducting contact and the conductor of the side plug.

9. A switch according to claim 8, and operating means for reciprocating said plunger said means comprising an adjustable connection for adjusting the gap between said contact and the conductor of the end plug in the open position of said switch.
